Patented June 16, 1964

198,460

TOY HOOP PADDLE

James R. McCollom, 11917 Claychester Drive,
Des Peres, Mo.

Filed Mar. 29, 1963, Ser. No. 74,220

Term of patent 3½ years

(Cl. D34—5)

FIG. 1 is a perspective view of a toy hoop paddle, showing my new design.

FIG. 2 is a fragmentary rear elevational view of the paddle.

FIG. 3 is a side elevational view of the paddle.

FIG. 4 is a top view of the paddle.

I claim:

The ornamental design for a toy hoop paddle, substantially as shown.
